UNITED STATES PATENT OFFICE.

CARL C. HINKLEY, OF DETROIT, MICHIGAN.

MOTOR MOUNTING.

Application filed June 30, 1920. Serial No. 393,003.

To all whom it may concern:

Be it known that I, CARL C. HINKLEY, a citizen of the United States of America, residing at Detroit, in the county of Wayne 5 and State of Michigan, have invented certain new and useful Improvements in Motor Mountings, of which the following is a specification, reference being had therein to the accompanying drawings.

10 The invention relates to motor mountings and more particularly to mountings for internal combustion engines upon motor vehicle frames. The main object of the invention is the provision of a construction which 15 permits of weaving and twisting of the motor vehicle frame in any direction without placing any stress upon the engine housing. The invention has for other objects the novel arrangements and combinations of parts as 20 more fully hereinafter set forth.

In the drawings:

Figure 1 is a side elevation partly in section of a construction embodying my invention;

25 Figure 2 is a top plan view thereof;
Figure 3 is a cross section on the line 3—3 of Figure 1;

30 Figures 4 and 5 are views similar to Figures 1 and 3 respectively, showing a modified construction.

1 is a leg or projection extending laterally from the crank case of an internal combustion engine. There are preferably three of these legs to provide a three point suspension 35 for the engine, one leg being at the front of the engine and the other two legs at the opposite sides thereof and near the rear. In the present instance the leg shown is at one side of the engine and supported upon a side 40 sill 2 of the motor vehicle frame. 3 is a pivot plate rigidly secured to the leg 1, by means of the bolt 4, which vertically passes through the outer end of the leg and threadedly engages the pivot plate, the nut 5 45 clamping the pivot plate against the lower face of the leg. The lower face of this pivot plate is convex both in a direction parallel to the longitudinal axis of the engine and at right angles thereto. 6 is a trunnion support 50 having a concave face corresponding in curvature to the lower face of the pivot plate and engaging the same, this trunnion support rotatably engaging in the bearing 7 rigidly secured to the side sill 2.

55 For maintaining the pivot plate in engagement with the trunnion support and at

the same time permitting of relative rocking movement in any direction, the coil springs 8 are provided at opposite sides of the leg 1 and surrounding the stud bolts 9, which 60 pass through the pivot plate 3 and are rigidly secured to the trunnion support 6 as by being threaded thereto. Nuts 10 threadedly engaging the upper ends of the stud bolts 9 force the coil springs 8 against the 65 pivot plate, suitable abutments 11, as washers being preferably provided between the coil springs and the nuts and the coil springs and the rocker arms. To permit of the ready moving of the parts, the apertures in the 70 pivot plate 3 through which the stud bolts 9 pass are sufficiently large to provide sufficient clearance to permit of the necessary relative movement of the pivot plate and trunnion support.

75 As shown in the modification of Figures 4 and 5 the pivot plate 12, which is secured to the leg 13 of the crank case, is mounted upon a support which is fixedly secured to the frame of the vehicle, instead of being 80 rotatably secured. In detail, the support comprises the pivot bearing 14 having a bearing face 15 which is concave both in a direction parallel to the longitudinal axis of the engine and at right angles thereto 85 and adapted to be rotatably engaged by the correspondingly convex bearing face of the pivot plate. This pivot bearing is mounted upon the bracket 16 rigidly secured to the vehicle frame. The spring pressed bolts 17 90 secure the pivot plate 12 and pivot bearing 14 to the bracket 16, the apertures in the pivot plate through which the bolts pass being of sufficient size to permit of the desired degree of rocking of the pivot plate upon 95 the pivot bearing.

What I claim as my invention is:

1. The combination with an engine, of a frame, a pivot plate secured to said engine and having a convex face curved in transverse direction, a support rotatably mounted upon said frame and having a concave face engageable with said convex face, and means engageable with the opposite end portions of said pivot plate for yieldably maintaining said pivot plate in engagement with said support.

100 2. The combination with an engine, of a frame, a leg upon said engine, a pivot plate secured to the lower face of said leg, and having a lower convex face curved in transverse directions, a support having a concave

2
surface engageable with said convex face and correspondingly curved, stud bolts secured to said support and extending through said pivot plate with clearances to permit 5 of relative rocking movement of said pivot plate and support, and springs surrounding said stud bolts for forcing said pivot plate toward said support.

3. The combination with a motor, of a 10 frame, a leg upon said motor, a pivot plate having a lower face curved in transverse directions, means for fixedly securing said pivot plate to said leg, a support having a face curved in transverse directions and in 15 engagement with the face upon said pivot plate, and means upon opposite sides of said leg and connected to said support for yieldably forcing said pivot plate toward said support.

20 4. The combination with a motor, of a frame, a trunnion support rotatably mounted upon said frame, a pivot plate rockably engaging said trunnion support in a plane transverse to the direction of rotation of said

trunnion support, means for fixedly securing 25 said pivot plate to said motor, and springs upon opposite sides of said securing means for yieldably forcing said pivot plate toward said trunnion support.

5. The combination with an engine, of a 30 frame, a leg upon said engine, a pivot plate secured to said leg, a support pivotally mounted upon said frame and rockably engaging said pivot plate, and means upon opposite sides of said leg engageable with said 35 pivot plate for yieldably maintaining said plate in engagement with said support.

6. The combination with a motor, of a frame, a leg upon said motor, a pivot plate secured to said leg and having a convex face, 40 a support pivotally mounted on said frame and having a concave face engaging the convex face of said plate, and means upon opposite sides of said leg for yieldably maintaining said pivot plate in engagement with 45 said support.

In testimony whereof I affix my signature.
CARL C. HINKLEY.
